UNITED STATES PATENT OFFICE.

CHARLES S. ELLIS, OF CHICAGO, ILLINOIS.

DIMMER DEVICE FOR HEADLIGHTS.

1,115,914.

Specification of Letters Patent.

Patented Nov. 3, 1914.

Application filed December 22, 1913. Serial No. 808,124.

To all whom it may concern:

Be it known that I, CHARLES S. ELLIS, a citizen of the United States, and a resident of Chicago, in the county of Cook and State of Illinois, have invented certain new and useful Improvements in Dimmer Devices for Headlights; and I do hereby declare that the following is a full, clear, and exact description thereof, reference being had to the accompanying drawings, and to the characters of reference marked thereon, which form a part of this specification.

This invention relates to a dimmer or mask for head lights for lamps for use on automobiles, locomotives, electric cars and the like, and refers more specifically to an improved device adapted to be applied to the lamp in the path of the light rays projected therefrom and arranged to be adjusted so that the full volume of the light may be projected directly, and without obstruction, from the lamp, and also arranged to be adjusted to deflect the light downwardly on the roadway in advance of the vehicle and to prevent the direct passage of the light forwardly to a person approaching the vehicle, and to thereby avoid the glaring effect of the full light.

Among the objects of the invention is to provide a simple, economical and compact device for the purpose set forth, and the invention consists in the matters hereinafter set forth and more particularly pointed out in the appended claims.

In the drawings:—Figure 1 is a front elevation of a lamp equipped with my improved dimming device. Fig. 2 is an axial section thereof. Fig. 3 is an enlarged detail of the pivot connection between one of the slats and the slat actuating bar.

In the particular embodiment of my invention which I have herein shown 10 comprises a casing, made preferably of sheet metal and of cylindric contour. The casing is provided at its rear end with a flange 11 adapted to be applied over and attached to the beaded rim 12 of the lamp front or door around the lamp lens, so that the casing is concentric with the lamp lens. Said casing 10 is preferably closed at its forward end by a sheet of glass or other transparent material 14 which is secured to the casing in any suitable manner.

Located within the cylindric casing 10 is a series of superposed slats 15 arranged horizontally between the front and rear of the

casing. Said slats are pivotally mounted in the casing by means of suitable pivots extending from the ends of the slats intermediate their front and rear edges. As herein shown, the pivots consist of rods 16 which extend throughout the lengths of the slats, and through suitable hollow ears or lugs 17 struck up from the slats, with the ends thereof extending beyond the ends of the slats for pivotal engagement with a ring 18 fixed in any suitable manner within the frame or casing 10, as shown in Fig. 2. The said slats are adapted to be simultaneously actuated to open and close the dimmer device by means of a vertically disposed bar 20, arranged in rear of the slats. Said actuating bar has sliding engagement in suitable openings 21, 22 at the upper and lower sides of the casing or frame, and is loosely connected to the said slats. A convenient method of connecting the bar to the several slats is to form holes 24 adjacent to and entirely inside of the front edge of the actuating bar 20 and to file notches 25 through the front edge of the said bar which intersects said openings. In this manner there is formed in each opening opposed contact points 26, 26, separated such a distance as to readily engage opposite sides of an adjacent slat. This construction constitutes a very efficient and simple pivot connection between the slats and the actuating bar, such as to give direct movement to the slats and to give the necessary relative movement to the slats and the bar due to the relative arcuate and reciprocatory movements of the said slats and bar. The said slats are made wide from front to rear thereof relatively to each other so that when adjusted in forwardly and downwardly inclined positions (one of their normal positions), as indicated in Fig. 2, the forward edge of each slat is below the rear edge of the next subjacent slat, so that the light rays do not pass directly and horizontally between the slats. The slats may thus be said to be arranged in inclined, overlapping relation.

The lower faces of the slats are provided with brightened or mirrored surfaces so that the reflected light which strikes the same is thrown downwardly and forwardly upon the roadway. In order to prevent the light thus reflected by the lower faces of the slats being again reflected forwardly in horizontal or forward direction, the upper sides of the slats are provided with non-reflecting or dull surfaces so as to thereby,

to an extent, absorb the light rays projected thereon, and to produce a dimming effect of the light as viewed from directly in front of the lamp. By making the slats relatively 5 wide, as shown in Fig. 2, it becomes practicable to throw the downwardly deflected light rays a considerable distance in advance of the vehicle, while avoiding the projection of said rays horizontally forward and directly 10 from the source of light within the lamp so as to produce a glaring effect in the eyes of a person approaching the vehicle. The appearance of the dimmed or masked light behind the dimmer, when adjusted as 15 shown in Fig. 2, is that of a soft subdued light, with the source of illumination, as the lamp in rear thereof, subdued so as not to produce a spot in the center of the resultant light or a glaring effect due to a directly 20 reflected light.

The actuating bar 20 is herein shown as provided at its lower end with a shoulder 27 which limits the downward movement thereof, and serves to hold the slats in 25 parallel horizontal positions, as indicated in dotted lines in Fig. 2. In this latter adjustment of the lamp the full, directly reflected light passes outwardly between the slats, and the slats are not visible. This effect, 30 therefore, is that of an unmasked light. That is to say, the slats do not cast a shadow in the driving light, nor do they produce any visible obstruction.

The slats may be locked in their downwardly inclined, deflecting positions in any 35 suitable manner, as by means of a spring latch 28 attached to the end of the actuating bar, which extends outwardly from the lamp casing to constitute a hand piece 29, the 40 said latch being adapted for frictional or interlocking engagement with the walls of the openings 22 through which the hand piece extends.

I claim as my invention:

45 1. A dimmer device for lamps comprising a series of rocking opaque slats arranged horizontally across the path of the light to be dimmed and adapted to assume, in one normal position, a forward and downward 50 inclination, but not closed, and of such

width relatively to their spacing that the rear edge of each slat is disposed in overlapping inclined relation to the forward edge of the next adjacent slat to shut off the horizontal passage of light between said slats, 55 and in another position to be presented edgewise to the source of light, the lower faces of said slats being reflecting surfaces, and the upper faces thereof being non-reflecting surfaces, means to simultaneously 60 rock said slats to open and partially close the dimmer device and means for locking the slats in both of their inclined light subduing and horizontal light displaying positions. 65

2. A dimmer device comprising a frame having means to attach same to the front of the lamp frame, a series of superposed horizontally arranged slats pivotally mounted in said frame, a reciprocatory actuating bar 70 having guiding engagement with said frame and provided along its length with a series of spaced two-point contacts for engagement with the marginal parts of said slats, and means for locking said actuating bar 75 and therethrough said slats in different positions of adjustment.

3. A dimmer device comprising a frame closed at its forward end by a transparent front and provided at its rear end with a flange by which to attach the same to the front of the lamp frame, a series of superposed, horizontally arranged rocking slats pivotally mounted in said frame, a vertically reciprocatory actuating bar having 85 guiding engagement with said frame and connected to the rear margins of said slats for simultaneously actuating same, and a spring latch carried by said bar for engagement with the casing to lock said slats in 90 different positions of adjustment.

In testimony, that I claim the foregoing as my invention I affix my signature in the presence of two witnesses, this 18th day of December, A. D. 1913.

CHARLES S. ELLIS.
